UNITED STATES PATENT OFFICE

118,190

DESIGN FOR A TEXTILE FABRIC OR SIMILAR ARTICLE

Benjamin B. Spatz, New York, N. Y.

Application April 1, 1939, Serial No. 83,973

Term of patent 3½ years

To all whom it may concern:

Be it known that I, Benjamin B. Spatz, a citizen of the United States, residing at New York, in the county of New York and State of New York, have invented a new, original, and ornamental Design for a Textile Fabric or Similar Article, of which the following is a specification, reference being had to the accompanying drawing, forming part thereof.

The single figure of the drawing is a plan view of the fabric showing my design. The drawing is lined for color contrasts.

I claim:

The ornamental design for a textile fabric or similar article, as shown and described.

BENJAMIN B. SPATZ.
